UNITED STATES PATENT OFFICE

138,218

DESIGN FOR AN AIRPLANE

Willem D. van Zelm, Ruxton, Md., assignor to The
Glenn L. Martin Company, Baltimore, Md.

Application May 31, 1943, Serial No. 110,338

Term of patent 14 years

(Cl. D71—1)

To all whom it may concern:

Be it known that I, Willem D. van Zelm, a citizen of the United States and a resident of Ruxton, in the county of Baltimore and State of Maryland, have invented a new, original, and ornamental Design for an Airplane, of which the following is a specification, reference being had to the accompanying drawing, forming part thereof.

Figure 1 is a top plan view of the subject airplane.

Figure 2 is a front elevational view of the airplane shown in Figure 1, the landing gear being in the retracted position.

Figure 3 is a side elevational view of same, the landing gear being in the retracted position.

I claim:

The ornamental design for an airplane, substantially as shown.

WILLEM D. VAN ZELM.
